UNITED STATES PATENT OFFICE.

HENRY C. MILLER, OF MILWAUKEE, WISCONSIN.

LOOSE-LEAF BINDER.

1,288,957.

Specification of Letters Patent. Patented Dec. 24, 1918.

Application filed May 7, 1917. Serial No. 166,872.

To all whom it may concern:

Be it known that I, HENRY C. MILLER, a citizen of the United States, and resident of Milwaukee, in the county of Milwaukee and 5 State of Wisconsin, have invented new and useful Improvements in Loose-Leaf Binders, of which the following is a description, reference being had to the accompanying drawings, which are a part of this specification.

10 This invention relates to improvements in loose leaf binders.

The invention relates more particularly to that type of binders in which the leaves are removably placed between side covers which 15 are movable toward and away from each other to adjustably clamp and hold leaves therebetween.

It is one of the objects of the present invention to provide a loose leaf binder in 20 which the leaves may be easily removed from or inserted in the binder and when inserted the leaves may be firmly locked in position.

A further object of the invention is to provide a loose leaf binder having extensible 25 flattened binding posts which may be revolved a partial turn to lock or unlock the leaves thereto.

A further object of the invention is to provide a loose leaf binder in which the binder 30 may be opened and extended to a working position whereby the leaves may be spaced apart and maintained in spaced position to permit the convenient removal or insertion of leaves.

35 A further object of the invention is to provide a loose leaf binder in which the locking posts are turned by a rack and gear connection actuated by a threaded member and nut.

40 A further object of the invention is to provide a loose leaf binder having means for easily opening and closing the cover portions to permit the convenient removal or insertion of leaves.

45 A further object of the invention is to provide a loose leaf binder in which the leaves are shaped to permit their easy engagement with the posts of the binder.

A further object of the invention is to provide a loose leaf binder which is of simple

construction, is strong and durable and is well adapted for the purpose described.

With the above and other objects in view the invention consists of the improved loose leaf binder and its parts and combinations 55 as set forth in the claims, and all equivalents thereof.

In the accompanying drawings in which the same reference characters indicate the same parts in all of the views:

60 Figure 1 is a perspective view of the improved loose leaf binder;

Fig. 2 is an inner side view of the back of the binder, the covers being shown in open position;

65 Fig. 3 is an end view of a portion of the binder with the back shown in partly expanded position and some of the leaves in spaced position;

Fig. 4 is a sectional view taken on line 4—4 70 of Fig. 3 with the back shown in expanded position;

Fig. 5 is a sectional view taken on line 5—5 of Fig. 2;

Fig. 6 is a sectional view taken on line 6—6 75 of Fig. 2; and

Fig. 7 is a transverse sectional view taken on line 7—7 of Fig. 6.

Referring to the drawings the numerals 8 and 9 indicate the side pieces forming the 80 covers, 10 the back portion proper, 11 and 12 the extensible back members and 13 the leaves of the improved binder. The back and extensible back members are preferably formed of stamped sheet metal and the back 85 portion 10 is provided with offset guide members 14 which extend into guide sockets 15 formed in the extensible back members 11 and 12. The offset guide members are mounted on the inner side of the opposite 90 ends of the back and extend transversely thereof and parallel to each other to maintain the extensible back members in parallel relation to each other in moving toward and away from each other.

95 A threaded rod 15 journaled in bearings 16 mounted medially on the back member 10 extends longitudinally of the length of the back and is provided with right and left handed threaded portions 17 and 18. Nuts 100

19 threaded on the threaded portions of the rod have pivotally connected to projecting portions 20 thereof the inner ends of pairs of links 21 which are held on the nuts by screws 5 22. The outer ends of the pairs of links are connected to the extensible back members 11 and 12 by pivot pins 23 and are reversely positioned in pairs with relation to each other so that as the nuts are drawn toward 10 each other the extensible back members will be pulled toward each other and when moved outwardly away from each other the extensible members will be pushed outwardly to open position. The threaded rod is turned 15 by a cranked key 24 which enters a key opening 10' of the back and engages the squared end 25 of the rod. The endwise movement of the rod is prevented by the shoulders 26, formed by reducing the diameter of the rod 20 at the portions engaged by the bearings 16, and which shoulders bear against the bearings.

The outer part of the metal forming each extensible back portion is bent longitudinally of its length in a half circle as indicated by the numeral 27 and is then extended at right angles to the back portions to form tubular side flanges 28 to which the covers 8 and 9 are connected by hinge connections 29. The spaces 30 and 31 formed by the tubular flanges serve to hold in part the mechanism for holding the leaves in position.

Tubular binding posts 32 and 33 extending through and journaled at their outer ends in the side flanges 28 extend toward and telescope each other in pairs as clearly shown in Figs. 2, 3 and 7 of the drawings. The posts are of oval form in cross section 40 and the posts 32 telescope over the free ends of the posts 33 and have beveled or rounded end portions 32' to permit the leaves 13 to freely slide over the joint of connection.

The posts 32 along one of their side portions of less diameter are formed with saw teeth 34 which incline toward the particular flange in which the posts are journaled. These teeth when turned upwardly serve to hold the leaves in spaced position as illustrated in Fig. 3 and is very desirable in removing or inserting leaves as it maintains the leaves in position.

The posts extend through the inner walls of the flanges and are provided with enlargements or washers 35 on opposite sides of the walls to prevent endwise movement of the posts and all of the posts extending through the flange wall and into the tubular space 31 have gears mounted thereon in lieu of the washers. A toothed bar 37 slidably mounted in the tubular space 31 has its teeth 37' in mesh with the gears 36 and rotates the same one quarter turn to open or closed position. The toothed bar 37 is

slidably held in position between the wall of 65 the flange 28 and guide members 38 fastened to the extensible back member 12.

A post actuating member 39 threaded through a portion 40 of the member 12 carries a collar 41 loosely journaled on a reduced portion 39' thereof which is provided with a laterally extending finger 41'. This finger projects loosely into a recess 42 formed in the tooth bar 37. The threaded member 39 turns loosely in the collar and 75 moves said collar and the toothed bar forwardly and rearwardly as the member 39 is turned inwardly or outwardly by the engagement of the cranked key 24 with the squared head or end 43 thereof. A key 80 opening 44 is formed in the extensible back member 12 to permit the engagement of the key with the threaded member 39.

The leaves 13 which are removably inserted between the side covers 8 and 9 are provided with post openings 45 near their inner edges and from which lead outwardly flaring slots 46. The openings 45 register with the posts and are of a diameter corresponding to the larger diameter of the posts to 90 permit the free turning thereof. The inner ends 46' of the slots correspond in width to the portions of the posts of less diameter so that when the posts are revolved a one quarter turn and the covers are expanded 95 outwardly as shown in Fig. 3 the leaves 13 may be freely removed and when the wide portions of the posts extend transversely of the slots of the leaves the leaves are locked in position.

In order to cover the mechanism in the back of the binder and form a flat support for the inner edges of the leaves the extensible back members are provided with plates 47, one of the plates being connected to each 105 extensible back and moving therewith and each plate formed in part of spaced tongues 47' which interfit the spaced tongues of the other plate and extend toward and overlap each other. The overlapping portions are 110 offset as indicated by the numeral 48 to form a flat surface for the leaves to rest upon.

The extensible back portions at their ends are guarded by upturned flanges 49 on the back portion 10. Openings 50 are provided in the back members 11 and 12 to receive angled brackets 51 for holding the binder in an upright and partly open position for convenience in use.

From the foregoing description it will be 120 seen that the binder is of very simple construction and is well adapted for the purpose described.

What I claim as my invention is:

1. A loose leaf binder, comprising a back 125 portion, extensible back members slidably connected thereto, revoluble binding posts journaled in the back members and extend-

ing toward each other, said posts in transverse section being of greater width in one direction than in another, side covers movably connected to the extensible back members, means for moving the extensible back members, a rack and toothed wheel means for turning the binding posts and a threaded rod means for moving the rack.

2. A loose leaf binder, comprising a back portion, extensible back members slidably connected thereto, flattened revoluble binding posts journaled in the extensible back members and telescoping each other, side covers hinged to the extensible back members, some of said posts having toothed wheels mounted on their journaled ends, a rack bar in mesh with the toothed wheels, a threaded rod carried by one of the extensible back members for reciprocating the rack bar, means for moving the extensible back members toward or away from each other, and leaves having openings and slots through which the binding posts extend.

3. A loose leaf binder, comprising a back portion, extensible back members slidably connected thereto, flattened revoluble binding posts journaled in the extensible back members and telescoping each other, side covers hinged to the extensible back members, some of said posts having toothed wheels mounted on their journaled ends, a rack bar in mesh with the toothed wheels, a threaded rod carried by one of the extensible back members for reciprocating the rack bar, means for moving the extensible back members toward or away from each other, and leaves having openings adjacent their inner edges through which the binding posts extend, said leaves also having flaring slots which extend flaringly outwardly from the openings to the inner edges of the leaves to permit the removal of the leaves when the posts are turned in a certain position.

4. A loose leaf binder, comprising a back portion, extensible back members slidably connected thereto, side covers hinged to the extensible back members, flattened revoluble binding posts journaled in the extensible back members and telescoping each other in pairs at their free ends for removably holding leaves, said pairs of posts having toothed wheels mounted on their journaled ends, a rack bar in mesh with the toothed wheels for turning the revoluble posts, a rod having a threaded engagement with one of the extensible back members, means for operating the threaded rod, a collar carried by the threaded rod and connected to the rack bar, leaves having openings adjacent their inner edges through which the binding posts extend, and means for moving the extensible back members toward and away from each other.

5. A loose leaf binder, comprising a back

portion, extensible back members slidably connected thereto, side covers hinged to the extensible back members, flattened revoluble binding posts journaled in the extensible back members and telescoping each other in pairs at their free ends, said pairs of posts having toothed wheels mounted on their journaled ends, a rack bar in mesh with the toothed wheels, a rod having a threaded engagement with one of the extensible back members, means for operating the threaded rod, a collar carried by the threaded rod and connected to the rack bar, leaves having openings adjacent their inner edges through which the binding posts extend, said leaves also having slots which extend flaringly outwardly from the openings to the inner edges of the leaves to permit the removal of the leaves when the posts are turned to a certain position, and a link and threaded rod means for actuating the extensible back members.

6. A loose leaf binder, comprising a back portion, extensible back members slidably connected thereto, side covers hinged to the extensible back members, flattened and toothed revoluble binding posts journaled in the extensible back members and telescoping each other in pairs at their free ends, said pairs of posts having toothed wheels mounted on their journaled ends, a rack bar in mesh with the toothed wheels, a rod having a threaded engagement with one of the extensible back members, means for operating said rod, a collar carried by the threaded rod and connected to the rack bar, leaves having openings adjacent their inner edges through which the binding posts extend, said leaves also having slots which extend flaringly outwardly from the openings to the inner edges of the leaves to permit the removal of the leaves when the posts are turned with their toothed portions extending away from the back portion, and a link and threaded rod means for actuating the extensible back members.

7. Binding posts for a loose leaf binder, consisting of flattened telescoping revoluble tubes having teeth formed along one of the side portions of less width of one of the tubes.

8. Binding posts for a loose leaf binder, consisting of flattened telescoping revoluble tubes having saw shaped teeth formed along one of the side portions of less width of the outer tube.

9. Binding posts for a loose leaf binder, consisting of a post member having teeth formed along one of its sides for holding in spaced relation the leaves which are held by said member.

10. In combination with leaves having openings, of a binding post therefor consisting of a post member having teeth

110

115

120

125

formed along one of the sides for holding the leaves in spaced relation when the post is turned to a certain position and permitting the free movement of the leaves on the post when turned in another position.

11. In combination with leaves having openings, of a flattened binding post therefor consisting of a post member having teeth

formed along one of the narrow sides for holding the leaves in spaced relation when the post is turned to a certain position and permitting the free movement of the leaves on the post when turned in another position.

In testimony whereof, I affix my signature.

HENRY C. MILLER.
